UNITED STATES PATENT OFFICE

2,537,523

PORTABLE VACUUM CLEANER

Clements A. Frost, Yakima, Wash.

Application April 9, 1948, Serial No. 29,041

2 Claims. (Cl. 183—36)

1

This invention relates to portable vacuum cleaner, and more particularly to a rug cleaning apparatus of the vacuum type wherein the rug is subjected to a beating action while it is being cleaned.

A main object of the invention is to provide a novel and improved commercial rug cleaning apparatus of the vacuum type which is very simple in construction, easy to operate and which is readily emptied when a rug cleaning operation is completed.

A further object of the invention is to provide an improved commercial rug cleaning machine which removes dirt from rugs by vacuum action, the rug being beaten during the suction of dirt therefrom so that dirt particles adhering to the rug are shaken free, the machine being relatively compact in size, light in weight and rugged in construction.

Further objects and advantages of the invention will become apparent from the following description and claims, and from the accompanying drawings, wherein:

Figure 1 is a fragmentary vertical longitudinal cross-sectional view taken through a rug cleaning machine constructed in accordance with the present invention.

Figure 2 is a fragmentary top plan view with parts in cross-section, of the rug cleaning machine of Figure 1.

Figure 3 is a side elevational view of the rug cleaning machine of Figure 1.

Figure 4 is a transverse vertical cross-sectional view taken on line 4—4 of Figure 2.

Figure 5 is an enlarged cross-sectional detail view taken through the suction rotor of the apparatus of Figure 1 on the line 5—5 of Figure 2.

Figure 6 is an enlarged cross-sectional detail view taken through the rug beating rotor of the apparatus on the line 6—6 of Figure 2.

Referring to the drawings, 11 designates a housing of sheet metal or the like provided with a detachable bottom pan 12, said pan being provided with wheels 13. The housing 11 is detachably secured to the pan 12 by means of draw bolts 14 at the upper marginal portions of the sides of the pan which engage suitable lugs carried by the bottom margins of the side walls of the housing. The housing 11 is formed to define a hollow forward intake section or extension 15, positioned forwardly of the pan 12, and forming an intake chamber. The housing 11 further comprises an intermediate passage 16 and an enlarged rear compartment 17, overlying the pan 12 and constituting a receiving

2

chamber. Secured to the rear compartment 17 of housing 11 is a porous flexible bag 18. Designated at 19 is a U-shaped handle bar whose arms are secured to the sides of housing 11. The end of bag 18 is connected to the intermediate portion of handle bar 19 by a strap member 20.

Journalled transversely in the rear compartment 17 is a shaft 21 provided with an external pulley 22. Mounted on housing 11 forwardly of compartment 17 is an electric motor 23. One end of the motor shaft is provided with a relatively large pulley 24 which is coupled to pulley 22 by a belt 25. The other end of the motor shaft is provided with a relatively small pulley 26. Journalled transversely in the intake section 15 is a shaft 27 having an external pulley 28. Pulley 28 is coupled to pulley 26 by a belt 29.

Secured to shaft 27 by arcuate clamping plates 30 and by bolts 31 passing through said clamping plates and threaded into shaft 27 are opposed flexible rotor vanes 32, 32 extending substantially the entire transverse width of intake section 15 and provided at their free ends with spaced metal ferrule elements 33. The vanes 32 are radially slotted at 34 to increase the flexibility of the end portions of the vanes whereby said vanes comprise axially spaced radial fingers which are independently yieldable with respect to each other. The bottom of intake section 15 is substantially open and is provided with a grid structure 35 to limit upward entry of a rug area into said intake section responsive to suction. The ends of the radial fingers sweep 36 through the apertures of said grid structure. As shown in Figure 1, when a rug area is deflected upwardly against the grid 35 by suction the flexible fingers of the beater vanes 32 may repeatedly strike said rug area and produce a beating action thereon.

Transversely secured to the side walls of housing 11 rearwardly adjacent the intake section 15 is an arcuate baffle plate 36 overlying the forward end portion of pan 12 in passage 16 whose action 45 is to deflect dirt-laden air downwardly and to cause the heavier dirt particles carried by the air current to be deposited in the pan 12 as said air current travels rearwardly in passage 16. The baffle plate 36 forms a reduced passage between the forward intake chamber and the pan 12, Figure 1.

Compartment 17 is provided with an intermediate vertical longitudinal partition wall 37 formed with an aperture 38 concentric with shaft 55 21. Designated at 38' is a bottom partition wall

provided in compartment 17 which defines with vertical wall 37 a blower or fan chamber 39. The rear end of blower chamber 39 communicates with bag 18 through an outlet opening 40 formed in the rear wall of housing 11. Said rear wall is formed with a transverse lower opening 41 and provided in the housing adjacent opening 41 is a transverse depending wall 42, defining with the sides of the housing a second reduced passage leading from the bag 18 into the top of the pan 12 at the rear end of the pan. Rotatably mounted on a transverse axis in the lower rear portion of housing 11 is a valve plate 43 which normally closes off bag 18 with respect to pan 12. When valve plate 43 is rotated to an open position, as shown in dotted view in Figure 1, dirt in bag 18 may be emptied into pan 12. The shaft of valve plate 43 is provided with an external operating lever 44. Valve plate 43 is normally held closed by gravity, but may be rotated to open position by means of lever 44.

Secured to shaft 21 in compartment 39 is a vertical disc 45 carrying a plurality of horizontal pins 46 arranged on a circle concentric with shaft 21 and extending adjacent the vertical partition wall 37. Pivottally carried on each pin 46 is a flexible flap member 47. When disc 45 rotates, flap members 47 are held outwardly by centrifugal force and provide blower action in chamber 39. This produces an air stream which enters the machine at the bottom of intake section 15, passes through passage 16 into compartment 17, enters fan chamber 39 through opening 38 and passes into bag 18 through outlet opening 40.

The suction at the bottom of intake section 15 elevates the rug area into engagement with grid 35 and allows beater vanes 32 to strike the rug area, as above described loosening the dirt particles carried by the rug. The air stream carries the dirt and dust from the rug into engagement with baffle plate 36, whereby most of the dirt is deposited in pan 12. The air stream carries the remaining dirt particles through blower chamber 39 into bag 18 where the dirt particles are trapped by the filtering action of said bag.

After a cleaning operation, the dirt in bag 18 may be emptied into pan 12 by opening flap valve 43. Pan 12 may then be detached from housing 11 and the dirt carried therein may be emptied into a suitable disposal receptacle.

The rotation of the beater vanes 32 takes place at a much slower rate than that of blower shaft 21 in view of the much smaller size of pulley 26 as compared with pulley 24 and the relatively large size of pulley 28 as compared with pulley 22.

While a specific embodiment of a rug cleaning apparatus has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a vacuum cleaner, a housing including a forward intake chamber and a rear receiving chamber, the intake chamber having an opening in its bottom and the receiving chamber having its bottom formed open, a pan removably mounted upon the receiving chamber to cover its open bottom, means within the housing for

forming a first reduced passage between the intake chamber and the forward end of the receiving chamber, the first reduced passage leading downwardly into the pan, means within the housing and forming a fan chamber in the receiving chamber, said fan chamber having an intake opening in its end and an outlet opening in its side near its top, means arranged within the receiving chamber and forming a second reduced passage near and beneath the fan chamber and leading into the upper end of the pan, the second reduced passage having an outer opening, a valve to cover and uncover the second reduced passage, a bag attached to the housing and covering the outlet opening of the fan chamber and the outer opening of the second reduced passage, a rotary fan within the fan chamber, and means to drive the fan.

2. In a vacuum cleaner, a housing including a forward intake chamber and a rear receiving chamber, the intake chamber having an opening in its bottom and the receiving chamber having its bottom formed open, an elongated substantially horizontal pan removably mounted beneath the receiving chamber for covering its open bottom, a transverse depending baffle plate mounted within the housing and forming with the sides of the housing a first reduced passage between the intake chamber and the forward end of the pan, wall means within the housing for forming a fan chamber in the receiving chamber, the fan chamber having an intake opening in its end and an outlet opening in its side near its top, a generally vertical wall arranged within the receiving chamber adjacent to the rear side of the fan chamber and forming a second reduced passage near and beneath the fan chamber and leading into the upper end of the pan at the rear end of the pan, the second reduced passage having an outer opening adjacent to the rear end of the pan, a normally substantially horizontal plate valve mounted within the second reduced passage for opening and closing such passage, a bag attached to the rear end of the casing and covering the outlet opening of the fan chamber and the outer opening of the second reduced passage, a rotary fan within the fan chamber, and means to drive the fan.

CLEMENTS A. FROST.
